(57) **CLAIM**

The ornamental design for a holder for a flexible container, as shown and described.

DESCRIPTION

FIG. 1 is a perspective view of a holder for a flexible container;

FIG. 2 is a top perspective view of the holder for a flexible container of FIG. 1;

FIG. 3 is a front elevation view of the holder for a flexible container of FIG. 1, the back of the holder being substantially a mirror image of the front;

FIG. 4 is a left elevation view of the holder for a flexible container of FIG. 1, the right side of the holder being substantially a mirror image of the left side;

FIG. 5 is a top plan view of the holder for a flexible container of FIG. 1;

FIG. 6 is a bottom plan view of the holder for a flexible container of FIG. 1; and,

FIG. 7 is a bottom plan view of a second embodiment of the holder for a flexible container of FIG. 1, the only difference being the bottom of the second embodiment does not include an opening, it being understood that all other surfaces are the same as those of the first embodiment.
